AIRPLANE MAIL LOADING AND UNLOADING DEVICE

Gus Burton, Wadley, Ga.

Application November 27, 1941, Serial No. 420,728

6 Claims. (Cl. 258—1.6)

This invention relates to an airplane mail bag delivering and receiving apparatus, and has for one of its objects the production of a simple and efficient means for picking-up mail bags or other containers by a moving airplane from a moving crane or support.

A further object of this invention is the production of a simple and efficient runway and moving crane which is so constructed as to facilitate the delivery of a mail bag and the like to and from a moving plane.

Another object of this invention is the production of a simple and efficient mail bag pick-up mechanism for facilitating the picking-up of mail and the like by a moving airplane.

Other objects and advantages of the present invention will appear throughout the following specification and claims.

In the drawings:

Figure 1 is a side elevational view of the mail bag delivering and receiving apparatus;

Figure 2 is a top plan view of the runway, certain parts being broken away;

Figure 3 is an enlarged longitudinal sectional view taken on line 3—3 of Figure 2;

Figure 4 is a vertical sectional view taken on line 4—4 of Figure 3;

Figure 5 is a vertical sectional view taken on line 5—5 of Figure 3;

Figure 6 is a vertical sectional view taken on line 6—6 of Figure 3;

Figure 7 is a horizontal sectional view taken on line 7—7 of Figure 3;

Figure 8 is a side elevational view of the airplane used in connection with the present invention, certain parts being broken away and one of the mail bag cranes being shown in relative position;

Figure 9 is a vertical sectional view taken on line 9—9 of Figure 8 looking in the direction of the arrow;

Figure 10 is a sectional view taken on the line 9—9 looking in the opposite direction of the arrow;

Figure 11 is a longitudinal sectional view taken on line 11—11 of Figure 9, certain parts being shown in elevation;

Figure 12 is a vertical fragmentary sectional view taken on line 12—12 of Figure 11;

Figure 13 is a fragmentary end elevational view of the runway and illustrating the roof sections which are adapted to cover the runway; and

Figure 14 is an enlarged end elevation of one 55

of the runway sections and a portion of the supporting track therefor.

By referring to the drawings, it will be seen that 10 designates the runway which is preferably elevated upon a frame-work structure 11. A plurality of rows of traction rollers 12 are arranged to extend slightly above the surface of the runway 10. The rollers of one row are preferably arranged in transverse staggered relation relative to the rollers of the adjoining rows, as shown in Figure 2. The runway 10 comprises side angle rails 13 and end rails 14, as well as a plurality of longitudinally extending inverted T-shaped roller supporting stringers 15 and 16. The traction rollers 12 are provided with spiral grooves as shown, and are journaled, as shown, upon the rails 13 and stringers 15 and 16. The spaces between the rollers 12 are filled with cement, concrete or similar material 17, and the runway is constructed so as to provide pockets for the rollers 12, which pockets may be suitably drained.

The stringers 16 define a longitudinal channel 18 throughout the major portion of the length of the runway 10. An upper trackway 19 is supported by the frame 11 just below the stringers 16 and a bottom trackway 20 is supported by the trusses 21 of the legs 22 of the frame 11, as shown in Figures 3 and 4. The upper trackway 19 is provided with a longitudinal slot 23, as shown in Figure 4. Suitable braces 24 brace the runway 10 upon the legs 22. Side cross braces 25 are also provided. A suitable base 26 is provided for the legs 22.

A crane carriage 27 is mounted upon the trackways 19 and 20 and is adapted to move longitudinally of the runway 10. This carriage 27 carries the upper rollers 28 and the lower rollers 29, the upper rollers 28 contacting the bottom face of the trackway 19 and the lower rollers 29 contacting the upper face of the trackway 20. The carriage 27 travels longitudinally between the upper and lower trackways, as shown in Figure 3. A crane-supporting plate 30 is carried by the upper ends of the vertical rods 31 of the carriage 27 and these rods are threaded for receiving the nuts 32 to hold the plate 30 in an adjusted vertical position to freely travel in the channel 18. A plurality of crane arms 33 are pivotally secured to the plate 30 and these arms 33 are arranged to swing upwardly and stand at an angle of approximately 45° pointing toward the pick-up airplane. Some of the arms 33 are adapted to be selectively used for supporting mail bags for delivery to an airplane approach.

ing one end of the runway 10, and other arms 33 are adapted to be swung at an opposite angle and to be selectively used for supporting mail bags for delivery to an airplane approaching the opposite end of the runway 10. The arms 33 are adapted to fall upon the plate 30 in the direction of travel of the pick-up plane after the mail bag has been removed. Each arm 33 is provided with a retaining hook at its outer end which opens in the direction of travel of the pick-up plane with which it is adapted to co-operate so that the pick-up airplane may easily remove a mail bag from the crane arms.

A catapult device 34 is located at each end of the frame 11 and is adapted to set the carriage 27 in motion as hereinafter described. Each catapult device 34 comprises a carriage-receiving fork 35 which is carried by an upwardly extending flat spring 36 secured at its lower end 37 to the frame 11. The upper end of the flat spring 36 is connected to one end of the plunger rod 38 by means of a link 39. The rod 38 is slidably mounted through the end wall 40 of the frame 11 and the spaced guide 41. An expansion coil spring 42 is interposed between the guide 41 and a collar 43 carried by the rod 38 to drive the rod 38 toward the carriage 27 when the rod 38 is released. A trigger 44 is pivoted, as at 45, above the rod 38 and this trigger 44 is provided with a forwardly extending finger 46 which carries a roller 47 for engaging a lug 48 carried by the rod 38, as shown in Figure 3, to hold the rod 38 in a retracted position. An upwardly extending finger 49 is carried by the trigger 44 and this finger 49 is engaged by a tension coil spring 50. One end of the spring 50 is anchored to the end wall 40 to normally pull the trigger 44 into locking engagement with the lug 48. The rearward extremity of the trigger 44 carries a roller 51 which is adapted to fit under and support the depending U-shaped bar 52 of the treadle plates 53. Two of the treadle plates 53 are preferably carried at each end of the frame 11. The plates 53 are hinged at their forward ends 54. A bell-crank lever 55 is pivoted at 56 to the end of the frame 11 and one end of the lever 55 is connected to the rod 38, as at 57. An operating rod 58 is connected to the opposite end of the lever 55 to facilitate the setting of the rod 38. Any suitable means may be attached to the rod 58 or lever 55 for operating the same, or the rod 58 may be manually depressed for setting the catapult 34, as shown.

The operation of the catapult 34 is as follows: The rod 58 is depressed thereby swinging the lever 55 to pull the rod 38 to a set position whereby the lug 48 is moved in front of the roller 47, the spring 50 automatically pulling the trigger 44 to the set position shown in Figure 3. The roller 51 of the trigger 44 when in this position will lift the treadle plates 53 to a set position. When the landing wheels of an approaching airplane strike the treadle plates 53, the trigger 44 will be depressed with the plates 53 and the roller 47 will be lifted out of engagement with the lug 48. The springs 36 and 42 will shoot the rod 38 inwardly toward the carriage 27 which is engaged by the fork 35 and the impact will drive the carriage 27 longitudinally of the runway 10 thereby enabling an airplane of proper construction as hereinafter described, to pick up a mail bag or other article supported upon the carriage while the carriage 27 is traveling in the same direction as the airplane and at a predetermined proper speed.

A pick-up airplane 60 is used with the present invention and a pick-up scoop 61 which is hinged

at its rear end 62 to the body of the airplane. The forward end of the scoop 61 is suspended upon adjustable hanger rods 63 which are connected in the hydraulic cylinders 64 with suitable pistons 65. The cylinders 64 are preferably mounted to permit a slight swinging movement as the rods 63 are raised and lowered to raise and lower the scoop 61. A reservoir 66 is carried by the airplane and communicates with the cylinders 64. A suitable two-way valve controls the passage of hydraulic pressure to the selected ends of the cylinders 64 to move the pistons 65 in the desired direction for raising and lowering the scoop 61.

Suitable center opening gates 67 are hinged near the sides of the body of the airplane and are adapted to normally close the bottom of the body of the airplane below the scoop when the scoop is retracted. Suitable spring hinges are provided to cause the gates to normally close and to permit the scoop to extend downwardly between the gates while swinging the gates to an open position, as shown. A receiving tray 68 is located at the rear upper end of the scoop 61 to receive the mail bag as it is forced up the scoop 61. As shown in Figure 9, the scoop is wider at its forward end than at its rear end, the scoop tapering inwardly as shown. Rollers 69 are carried by the scoop to facilitate the passage of a mail bag and the like upwardly of the scoop toward the receiving tray 68.

A compartment 70 is located in the body of the airplane 60 in the rear of the receiving tray 68 and this compartment 70 carries a distributing desk 71 which may be located in any suitable or desired manner preferably around two sides of the compartment 70. The compartment 70 is provided with an inwardly swinging spring-actuated door 72 at the top thereof to permit mail bags to be placed within the compartment 70 and a spring pressed door or dropping gate 73 is carried by the bottom of the compartment or receptacle 70, and this gate 73 is so supported as to normally remain in a closed position but to open when the same is released by the control latch 74 which may be of suitable structure.

A transversely extending channel trackway 75 is carried at each end of the runway 10, and this trackway 75 extends laterally beyond the sides of the runway. A pair of roof sections 76 extend longitudinally of the runway and these roof sections 76 are carried by rollers 77 which travel in the trackways 75. The roof sections 76 are provided at each end with overhanging arms 78 which arms are adapted to overhang the trackways 75 and shield these trackways so as to prevent snow, ice and the like, from accumulating within the trackways 75 when the roof sections 76 are closed. The roof sections 76 are provided with suitable overlapping flanges 79 at their abutting edges to provide a weather seal for the roof sections 76 when the roof sections 76 are in a closed position. Suitable sprocket wheels 80 may be carried by the shafts or axles which support the rollers 77 and chains 81 are passed over the sprocket wheel or wheels 80 so that these chains may be reached by an operator and by pulling the chains the sprocket wheels 80 may be rotated imparting rotary movement to the rollers 77, in this way facilitating the movement of the roof sections to and from a closed position over the runway 10.

From the foregoing description it should be understood that the loading and unloading mail plane approaches the runway 10 and when the wheels of the plane strike the treadle plates 53,

the trigger 44 will be depressed thereby releasing the catapult 34 and setting the carriage 27 in motion to travel in the direction of the arrow indicated on Figure 1. The mail bags or other articles carried by the crane 33 which may be of suitable length are picked up by the scoop 61 and the momentum of the plane will cause the mail bag or other article to roll up the inclined scoop to the position where the mail bag is deposited in the receiving tray 68. When delivering mail an operator may release the latch 74 and a mail bag or other article will drop as the door 13 opens and fall from the bottom of the plane upon the runway 10, the bag passing over the traction rollers 12 and the speed of travel of the bag will be gradually decreased as the mail bag or other article passes over the intermediate sections between the traction rollers of the runway. The traction rollers 12 also facilitate the passing of the plane over the runway.

As illustrated, a catapult is arranged at each end of the runway, the runway may be of any suitable or desired length to provide proper momentum for the traveling carriage which supports the mail to be loaded and to receive the mail which is unloaded from the moving plane. The speed at which the carriage travels may be regulated by the strength of the springs and the catapult structure 34.

It should be understood that certain detail changes in the mechanical construction may be employed without departing from the spirit of the invention, so long as such changes fall within the scope of the appended claims.

Having described the invention, what is claimed is:

1. An apparatus of the class described comprising a runway, a plurality of vertically spaced trackways mounted adjacent the runway, a carriage mounted between and movable longitudinally upon the trackways and also movable longitudinally of the runway, said runway having a longitudinally extending channel, a crane-supporting plate mounted upon the carriage and adapted to travel in said channel, article-supporting cranes pivotally mounted upon said crane-supporting plate and movable to and from an operative position, and catapult means adapted to be actuated by a co-operating aircraft for setting said carriage in motion.

2. An apparatus of the class described comprising a runway, a plurality of vertically spaced trackways mounted adjacent the runway, a carriage mounted between and movable longitudinally upon the trackways and also movable longitudinally of the runway, said runway having a longitudinally extending channel, a crane-supporting plate mounted upon the carriage and adapted to travel in said channel, article-supporting cranes pivotally mounted upon said crane-supporting plate and movable to and from an operative position, catapult means adapted to be actuated by a cooperating aircraft for setting said carriage in motion, said plate being vertically adjustable on said carriage.

3. An apparatus of the class described comprising a trackway, a runway extending in a sub-

stantially horizontal plane and also extending longitudinally of and upon either side of said trackway, a carriage mounted for longitudinal movement upon the trackway, catapult means mounted at one end of the trackway and adapted to set said carriage in motion, said catapult means comprising a carriage-engaging member, a spring-pressed actuating rod, a stop lug carried by the actuating rod, a trigger for holding said actuating rod in a retracted position, said trigger having a lug-engaging end for engaging said stop lug, and treadle means engaging the opposite end of said trigger and adapted to actuate the trigger for releasing the trigger from said actuating rod.

4. An apparatus of the class described comprising a trackway, a runway extending in a substantially horizontal plane and also extending longitudinally of and upon either side of said trackway, a carriage mounted for longitudinal movement upon the trackway, catapult means mounted at one end of the trackway and adapted to set said carriage in motion, said catapult means comprising a carriage-engaging member, a spring-pressed actuating rod, a stop lug carried by the actuating rod, a trigger for holding said actuating rod in a retracted position, said trigger having a lug-engaging end for engaging said stop lug, treadle means engaging the opposite end of said trigger and adapted to actuate the trigger for releasing the trigger from said actuating rod, and means for holding said lug-engaging end of said trigger in engagement with said lug for holding said actuating rod in a set position.

5. An apparatus of the class described comprising a trackway, a runway extending in a substantially horizontal plane, and also extending longitudinally of the trackway, a carriage mounted for longitudinal movement upon the trackway, article-supporting means mounted upon the carriage, means for vertically adjusting the article-supporting means upon the carriage to support the article-supporting means in proper relative position relative to the runway, and article-supporting cranes pivotally mounted upon said article-supporting means and movable to and from an extended position in a manner whereby said cranes may selectively be supported in an article-supporting position and in an inactive retracted position.

6. An apparatus of the class described comprising a longitudinally extending elongated runway, a trackway extending longitudinally of the runway, treadle means located adjacent one end of the runway in a position to receive the landing gear of an airplane and directly engageable by the landing gear, an article-supporting carriage carried by and movable longitudinally of the trackway to permit an article to be lifted from said carriage by an airplane passing over said runway, driving means for moving said carriage longitudinally of the trackway, and means actuated by said treadle means for rendering said driving means active when the landing gear of an airplane directly engages said treadle means.

GUS BURTON.
